[57] CLAIM

The ornamental design for a key-mounted flashlight, as shown and described.

DESCRIPTION

FIG. 1 is a side elevational view of a key-mounted flashlight showing my new design;

FIG. 2 is the opposite side elevational view thereof;

FIG. 3 is a top plan view thereof;

FIG. 4 is a bottom view thereof;

FIG. 5 is a rear view thereof;

FIG. 6 is a front view thereof; and

FIG. 7 is a perspective view thereof.

The key is shown in broken lines for illustrative purposes only.
